CROSSING GATE

Dwight Richards and Samuel T. Comfort, Harvey,
Ill., assignors to The Buda Company, Harvey,
Ill., a corporation of Illinois

Application August 5, 1942, Serial No. 453,628

2 Claims. (Cl. 39—7)

Our invention relates to crossing gates and more particularly to crossing gates of the kind used at the intersection of a highway and a railroad and at other similar intersections.

An object of our invention is to provide a crossing gate which is of simple construction, inexpensive to manufacture and which is reliable and trouble free in use.

Another object of our invention is to provide a crossing gate which may be easily inspected and wherein any necessary adjustments or repairs may be readily made.

Another object of our invention is to provide a crossing gate which may be set to operate at any desired speed within wide limits.

Another object of our invention is to provide a crossing gate which is gravity lowered and wherein the lowering speed may be accurately adjusted over a wide range.

Another object of our invention is to provide a crossing gate having a new and improved control for regulating the rate at which the gate is lowered.

Another object of our invention is to provide a crossing gate which can be installed on either side of its supporting post and which can be readily adapted to swing in either direction.

Another object is to provide a new and improved crossing gate which will swing laterally when struck by an automobile or other vehicle and which will return to normal position after the vehicle has passed.

Other objects and advantages will become apparent as the description proceeds.

In the drawings:

Fig. 1 is a side elevation of a crossing gate embodying our invention, parts being shown in section to illustrate more fully their construction;

Fig. 2 is a view taken on the line 2—2 of Fig. 1;

Fig. 3 is an irregular horizontal section taken on the line 3—3 of Fig. 2;

Fig. 4 is a vertical section taken on the line 4—4 of Fig. 2; and

Fig. 5 is a wiring diagram showing the control circuits.

Referring to the drawings, it will be seen that we have illustrated our invention as being embodied in a crossing gate comprising a supporting post 10 carrying a pair of track members 12 and 14 bolted together and forming an inclined V-shaped track for a roller 16 attached to the base of a housing 18 which carries the gate arm and gate arm operating mechanism. The housing has a pair of rearward extensions 20 and 22 carrying rollers 24 and 26 which bear

against the supporting post 10. A pair of rods 28 and 30 is mounted in each rearward extension 20 or 22 and a casting 32 is bolted or otherwise secured to the ends of each pair of rods and

5 carries a second pair of rollers 34 and 36. From the foregoing, it will be apparent that the weight of the housing 18 rests entirely upon the track provided by the track members 12 and 14 and that the movement of the housing along this 10 track is guided by the rollers 24, 26, 34 and 36 which permit the housing to swing about its supporting post 10.

An electrical motor 38 is mounted in a compartment 40 provided in the housing 18 and 15 drives a motor shaft 42 carrying a pinion 44 and a ratchet wheel 46. The pinion 44 drives gear 48 integral with a sleeve 50 having pinion 52 formed thereon. The sleeve 50 is rotatably mounted by needle bearings 54 and 56 on a supporting rod 58 mounted in housing walls 60 and 62.

Pinion 52 drives large gear 64 keyed to a sleeve 66 rotatably mounted by needle bearings 68 and 70 on a second supporting rod 72 mounted in 25 wall 62 and an offset bracket 74 integral with partition wall 60. Pinion 76 is formed on sleeve 66 and drives gear 78. Gear 78 is keyed to sleeve 80 which is rotatably mounted on rod 56 by needle bearings 82, 84 and 86.

30 Pinion 88 is formed on sleeve 80 and drives segment gear 90 keyed to gate arm shaft 92 (Fig. 1). As best shown in Figs. 2 and 3, gate arm shaft 92 is rotatably supported by needle bearings 94 carried in bearing members 96 and 98, 35 integral with housing walls 100 and 62, respectively. The gate arm shaft 92 has directly mounted thereon side members 102 and 104 of the gate arm which may be provided with any suitable counterweights in accordance with the 40 usual custom.

The gate arm is adapted to be lowered by gravity and we have provided a special mechanism for controlling the rate to which this gate arm is lowered. This mechanism is best shown in 45 Fig. 1 and comprises a dashpot cylinder 106 having a reciprocal piston 108 attached to a piston rod 110 passing through a suitable packing gland 112 formed in the cylinder head 114. The upper end of the piston rod is connected by pivot

50 116 to an arm 118 attached to the segment gear 90. The piston 108 is provided with check valves 120 which permit substantially free flow of fluid through the piston during its upward stroke, i. e., while the gate arm is being raised under the 55 power of the motor 38.

The dashpot cylinder 106 is supported on pivot pins 122 mounted in bosses 124 provided by the housing 18 so that the cylinder 106 may automatically adjust itself to the position of the piston rod 110 as arm 118 and sector gear 90 rotate with gate arm shaft 92. Dashpot cylinder 106 is provided with a fixed port 126 permitting relatively free flow of fluid therethrough between the cylinder 106 and a bypass passageway 128. A plurality of spaced ports 130, 132, 134 and 136 are spaced lengthwise of the cylinder 106 and also connect this cylinder with the bypass passageway 128. These latter ports are controlled by needle valves 138, 140, 142 and 144, respectively, and these needle valves may be independently adjusted to provide any desired rate of descent for the gate arm.

When the gate arm is at its extreme upward position, as indicated in Fig. 1 of the drawings, the segment gear 90 engages a resilient stop 146 and when the gate arm is in the down or horizontal position, the other end of this segment gear 90 engages a second resilient stop 148. These stops are adjustable to provide any desired variations in travel of the gate arm and different strength springs may be substituted in these stops to adapt them for use with gate arms of widely varying weights.

In Fig. 1 of the drawings, the main portion of the gate arm extends to the left of housing 18 when the gate arm is in horizontal position. If it is desired to mount the gate arm on the shaft 92 so that the main portion of the gate arm extends to the right of this housing, the dashpot cylinder 106 is shifted so that its supporting pivot pins 122 are located in bosses 150 instead of bosses 124 and pivot 116 is shifted to bore 152 to connect the upper end of piston rod 110 with the other end of segment gear 90. By these simple changes the gate arm can be adapted to extend either to the right or left of the housing 18 and this housing can be mounted on either side of supporting post 10 for either direction of operation of the gate arm. This is particularly advantageous where our improved crossing gate is mounted on a support which has heretofore been in use, since it permits our crossing gate to be installed without interfering with signal lights and other signal mechanism theretofore in use.

It is desirable to provide means whereby the operating mechanism may be lubricated at periodic intervals and the means which we have provided to accomplish this result is best shown in Fig. 3. In this figure the gate arm shaft 92 is illustrated as being provided with a lubricant receiving fitting 154 communicating with ducts 156 and 158 leading to the needle bearing 94. It will be understood that similar means may be provided for lubricating the needle bearing at the other end of this shaft. Similarly, rods 58 and 72 are illustrated as being provided with lubricant receiving fittings 160 and 162, respectively, and it will be understood by those skilled in the art that these rods are provided with suitable ducts not shown for conducting this lubricant to the various needle bearings mounted on these shafts.

The gate arm is held in vertical position by a spring pressed latch 164 mounted on an arm 168 pivoted at 170 to partition 60. A link 172 connects the arm 168 with the arm 174 of a bell crank lever 176 pivoted on a stud 178 mounted on partition 60. An armature 180 is adjustably mounted on the bell crank lever 176 and cooperates with a pair of pull-up coils 182 and a second armature 184 is also adjustably mounted on the

bell crank lever 176 and co-acts with a pair of holding coils 186.

As shown in the wiring diagram (Fig. 5) the motor 38 is in a circuit which is opened and closed by a control relay 188 and including an overload thermal relay 190 which is inactive during the normal operation of the crossing gate. A second circuit is in parallel with the motor 38 and includes a limit switch 192 and pull-up coils 182.

The control relay 188 has a coil 194 located in a circuit which includes a limit switch 196 and track relay 198 and a circuit containing the holding coils 186 is in parallel with coil 194 and limit switch 196. The track relay 198 has a coil 200 which is connected to the rails of the railroad track and is energized by the track circuit.

The limit switches 192 and 196 are preferably mercury switches which are opened or closed by tilting. These switches are independently mounted on the gate arm shaft 92, as indicated at A in Fig. 4, and each switch may be independently adjusted so that these switches open or close at any desired positions of the gate arm.

All of the operating mechanism and switch controls are enclosed in the housing 18. This housing is provided with a hinged door 202 which is normally held in closed position by a latch 204. A padlock may be attached to the staple 206 to prevent unauthorized persons from opening the door 202 and tampering with the gate operating mechanism. We shall now describe the operation of our new and improved crossing gate.

When the gate is in normal or raised position, current flowing in the track circuit energizes coil 200 and holds relay 198 in closed position. This maintains closed the circuit to the holding coils 186 and these coils hold latch 164 in engagement with the ratchet wheel 46 and thus prevent the gate arm from falling under the force of gravity. In this position of the parts, limit switches 192 and 196 and control relay 188 are in the position shown in Fig. 5.

When an approaching train short circuits the track, circuit relay 188 drops and breaks the circuit leading to holding coils 186. The resulting de-energization of these coils permits pawl 164 to move away from ratchet wheel 46 under the influence of gravity acting upon this pawl and its associated parts and under the force exerted by the ratchet wheel under the gate arm load. Thereupon the gate arm starts to lower under the force of gravity acting thereon.

While the force tending to lower the gate arm decreases as this gate arm approaches horizontal position, the result would still be a continued increase in the speed of descent of the gate arm unless some control means were provided to check this descent. In our improved crossing gate we accurately control this rate of descent by the dashpot cylinder 106 and its associated mechanism. When the gate arm and piston 108 are at the upper ends of their movement, that part of the cylinder 106 which is beneath the piston is in substantially free communication with the bypass 128, but the upper end of this bypass communicates with the upper end of cylinder 106 through only the single port 136 which greatly restricts flow of the low temperature oil from the bypass to the upper end of the cylinder and thus retards downward movement of the piston 108 and the gate arm connected therewith.

As the piston moves further down in the cylinder 106, the piston reaches a point where it is below port 134 and this port cooperates in re-

turning fluid to that part of the cylinder above the piston, thereby decreasing the resistance to the descent of the piston. As the piston passes below port 132, the resistance to its descent is further decreased. Preferably these decreases in resistance correspond to decreases in torque exerted by the gate arm and serve to maintain a substantially constant speed of descent of the gate arm and piston. Port 126 provides relatively free flow of fluid between the cylinder 106 and bypass 128 and as soon as a piston passes below this port its rate of descent is materially reduced by reason of the fact that all fluid below the piston must pass from the cylinder to the bypass through restricted port 130. This lower port 130 thus controls the cushioning effect of the dashpot and this cushioning effect can be varied by adjusting the needle valve 138. Similarly the first part of the downward movement of the gate arm can be adjustably controlled by adjusting needle valves 140, 142 and 144 so that any desired rate of descent can be obtained.

It is usual to provide lights, bells and similar signal mechanism to cooperate with the crossing gates in warning pedestrians and vehicle operators of the approach of trains. Such signal mechanisms are commonly controlled by the position of the gate arm and with our new and improved crossing gate this can be easily accomplished by mounting the control switches on the gate arm shaft 92 so that such signal means will be set in operation as the gate arm descends and turned off as the gate arm is raised. Our crossing gate, however, is not limited to such control of the signaling mechanism and any other usual or suitable manner of controlling this mechanism may be provided.

As the gate arm descends, limit switch 192 is opened and remains open until the gate arm again approaches the upper limit of its movement. Opening of this limit switch produces no effect, since the circuit of which it forms a part remains broken, as shown in Fig. 5.

After the gate arm is moved downward through an angle of approximately 5°, limit switch 196 closes and remains closed until the gate arm is again raised to within approximately 5° of its upper limit of movement. This likewise produces no effect, since the circuit of which this limit switch forms a part is broken by track relay 198.

After the train has passed, coil 200 is again energized by the track circuit and closes the track relay 198, thereby energizing holding coil 186 and control relay 188. The holding coils 186 are too weak to raise pawl 164 into engagement with ratchet wheel 46 and thus the energization of these coils is without effect. The energization of control relay 188, however, closes the motor circuit and motor 38 is energized and starts raising the gate arm.

The speed at which the gate arm is raised will depend upon the angle through which this gate arm must be raised, the speed at which the motor operates, and the particular sizes of gears and pinions which are interposed between the motor and gate arm. With a motor operating at a conventional speed, such as 1725 R. P. M., the speed of raising the gate arm may be varied from 4½ seconds to 8 seconds for a 90° movement by simply changing the size of the motor pinion gear 44 within permissible limits. This variation in rate of lift of the gate arm is sufficient to meet practically all conditions, but special

conditions may be provided for by using a motor having a different operating speed or by using different sized gears in the gear train connecting the motor pinion with the gate arm shaft.

During the upper movement of the gate arm, oil in that part of the dashpot cylinder which is above the piston 108 flows freely through the check valves 120, provided in this piston, and offers substantially no resistance to the upward movement of the piston. As the gate arm reaches a position approximately 10° before its upper limit of movement, limit switch 192 closes, thereby energizing pull-up coils 182. These coils are powerful coils of relatively low resistance and cooperate with the relatively weak holding coils 186 to pull the pawl 164 into engagement with the ratchet wheel 46. This brings the pawl 164 into engagement with ratchet wheel 46 while this wheel is still rotating, but the resilient mounting of the pawl 164 prevents injury to pawl 164 when it is brought into engagement with the rotating wheel.

Just before the gate arm reaches the upper limit of its movement, limit switch 196 opens, thereby de-energizing control relay 188, whereupon this relay breaks the circuit to the motor 38 and pull-up coils 182. Holding coils 186, however, remain energized and have sufficient strength to maintain pawl 164 in engagement with ratchet wheel 46 so that no retrograde movement of the wheel or corresponding downward movement of the gate arm may occur. The holding coils are of high resistance and require but an exceedingly small current which creates no appreciable drain on the battery or other source of current supply for the gate operating mechanism.

If the gate arm is struck by an automobile or other vehicle while in lowered position, the gate arm and housing 18 containing the operating and control mechanism can swing as a unit about the supporting post 10 and by thus yielding with the impact avoid injury to the gate arm and its associated mechanism. As the gate arm and housing swing about the post 10, roller 16 rides up one side of the inclined track provided by the members 12 and 14 mounted on the post. The lateral swinging of the gate arm and its operating mechanism is resisted by the action of gravity so that the lateral movement of this arm is no greater than is necessary to permit the gate to accommodate the movement of the vehicle and as soon as the vehicle has passed the gate arm returns automatically to normal position transversely of the highway.

When it is desired to paint or repair the gate arm, it is usually desirable to have the gate arm in lowered position but undesirable to have the gate arm extending across the highway while the painting or repair is being effected. We have, therefore, provided the track for the roller 16 with a retaining notch 210 so that prior to making the repair the gate arm can be swung until the roller 16 engages and is held in this notch. In this position the gate arm will extend parallel to the highway and not interfere with traffic along the highway. After the repair has been completed a slight lateral push on the gate arm will cause the roller 16 to roll down the track to the position shown in Fig. 1.

In most installations it is desirable to mount the gate arm so that it will swing laterally if struck by an automobile or other vehicle and we have illustrated and described a preferred embodiment of our invention as being mounted to

provide such lateral swinging movement. In some installations, however, such lateral swinging movement is not necessary or desirable and in these latter installations the track 14 and rollers 16, 24, 26, 34 and 36 can be eliminated and the housing 18 rigidly and firmly secured to the supporting post 10.

The particular crossing gate which we have illustrated and described has been designed to fulfill the needs of a totally automatic gate. While this gate is designed to lower by gravity, power lowering can be provided by installing an instantly reversible motor, together with the necessary control equipment which is readily available on the open market. This change would not destroy the ability of the gate to lower by gravity and would be of advantage in only a few special installations which were intended to satisfy unusual conditions.

While we have illustrated and described only a single embodiment of our invention, it will be understood that our invention may assume numerous forms and that the scope of our invention is defined by the following claims.

We claim:

1. In a crossing gate of the class described, the combination of a gate arm movable in a vertical plane, power operated means for raising said gate

arm, said gate arm being adapted to descend under the force of gravity, a housing for said power operated means, a supporting post for said housing, and reversible control means for regulating the descent of said gate arm and permitting the main portion of said gate arm to extend in either direction from said housing, said reversible control means including a dashpot cylinder, a pair of pivotal mountings therefor, a piston reciprocable in said cylinder, a piston rod attached to said piston, and a segment gear attached to said gate arm and having means at each end thereof for attachment to said piston rod.

2. In a crossing gate of the class described, the combination of a gate arm movable in a vertical plane, means for raising and lowering said gate arm and permitting the main portion of said gate arm to extend in either horizontal direction, reversible control means including a dashpot cylinder, a pair of pivotal mountings therefor, a piston reciprocable in said cylinder, a piston rod attached to said piston, and a segment gear attached to said gate arm and having means at each end thereof for attachment to said piston rod.

DWIGHT RICHARDS.
SAMUEL T. COMFORT.
